AIR CONDITIONING SYSTEM

Robert B. P. Crawford, Brooklyn, N. Y., assignor
to Frick Company, Waynesboro, Pa., a corpora-
tion of Pennsylvania

Application April 28, 1932, Serial No. 607,916

29 Claims. (Cl. 257—1)

This invention relates, in general, to air conditioning systems and, more particularly, to a system which, although of general application, is especially suited for installation in hotels, apartments, hospitals, and similar buildings wherein it is desirable, or necessary, to maintain different, or varying air conditions in different parts of the building.

In the prior types of ventilating and air conditioning systems used in buildings of the kinds mentioned, air is circulated from a central air conditioning unit through ducts to the floors or rooms and back to the unit, or exhausted to the atmosphere. By reason of the large amount of duct work necessary, such systems are very expensive and take up an inordinate amount of space. Furthermore, since all of the conditioning of the air, both as to the humidity and temperature, is effected at the central unit and is controlled by the operator of the unit, the air entering each floor or room is at the same temperature and relative humidity.

To obtain some degree of individual control of the air temperature at the various floors or rooms, various arrangements, such as the provision of dampers in the air outlet ducts and/or air inlet ducts, the provision of heat exchangers in the floors or rooms, etc., suggest themselves. These arrangements, when considered in the light of the teachings of the prior art, are not satisfactory. The use of dampers can give only a limited control and seriously interferes with the air circulation; the use of heat exchangers involves, besides the exchangers themselves and the piping necessary for the circulation of the heat exchange fluid, additional piping for conducting away water which may condense on the exchangers due to their temperature being brought below the dew point of the conditioned air. Furthermore, whether heat exchangers or individual conditioning units are used, it is always necessary to thoroughly insulate all piping through which the heat exchange medium is circulated to prevent condensation of moisture on such piping. For these reasons, the present practice is to use separate air conditioning units in each floor, or room, whenever it is necessary to provide for individual control at the floors or rooms.

In the known systems using a central unit for supplying conditioned air to a plurality of separate floors, or rooms, it is necessary that the pressure conditions throughout the whole system be maintained substantially constant at predetermined values, in order that every floor or room be supplied with its required amount of condi-

tioned air. If the predetermined pressure conditions in any part of the system are not maintained, as for instance, if a window, or windows, in any of the floors or rooms, are opened, the result is that either the amount of conditioned air fed to each floor or room is changed or an increased amount of air is passed through the air conditioning unit and none of the floors or rooms gets the desired amount of properly conditioned air. In any event, the whole ventilating system is disorganized until the predetermined pressure conditions throughout the whole system are again established. This disadvantage has not been overcome in any of the known systems of the art.

The known air conditioning units are all designed to take in atmospheric air or a mixture of atmospheric and recirculated air, and in one step, cool and dehumidify it. The air thus conditioned is then passed directly to the point or points of use, or, as in some cases, heated to a desired temperature, and then passed to the point, or points, of use. By this procedure, a greater load than necessary is carried by the dehumidifier and no attempt is made to efficiently use the energy supplied to the system.

This invention is directed to a solution of all the problems above mentioned and has for an object an air conditioning system adapted to supply conditioned air from a central air conditioning unit to a plurality of floors or rooms of a building which provides for further controlled conditioning of the air at the individual floors or rooms and which permits the altering of pressure conditions in any of said floors or rooms without in any way affecting the conditioning of the air at the central unit or at the rest of said floors or rooms or altering the quantity of air fed to the rest of said floors or rooms, said system involving a minimum of duct work and apparatus and entirely eliminating the need of insulation on the piping used for circulating heat exchange medium.

The invention has also for an object a mechanism which may be used in any type of ventilating or air conditioning system wherein air is supplied to a plurality of enclosures, which mechanism will automatically cut out any enclosure or enclosures from the system when the pressure conditions in said enclosures change from those necessary for the proper operation of the system and will automatically restore said enclosure or enclosures to the system when the pressure conditions necessary for the proper op-

eration of the system again attain in said enclosure or enclosures.

In accordance with my copending application, Ser. No. 375,952, filed July 5, 1929 a system is disclosed wherein outside air is conditioned before being admitted to the enclosure, the pressure within the enclosure being maintained above atmospheric pressure to prevent infiltration of air except from the conditioner, and a separate conditioning of the air in the enclosure, and the commingling in the enclosure of the two streams of air produced by the two conditioners. With respect to such subject matter this application is a continuation in part.

The invention has for a further object an air conditioning and ventilating system wherein conditioned air is supplied to the floors or rooms of the building under a pressure sufficient to prevent infiltration of air from the atmosphere and to allow a definite quantity of air to flow from the floors or rooms to the atmosphere, and wherein ventilating and heat exchange means are provided in each of the floors or rooms for continuously mixing the air supplied to each floor or room with the air in the floor or room and for continuously modifying the temperature of mixed air to maintain it at a desired temperature; the heat exchange medium supplied to the heat exchangers in said floors or rooms being passed through the dehumidifying zone of the central air conditioning unit in heat exchange relation with the air being dehumidified before it is supplied to the heat exchangers so that the temperature of the heat exchangers and the piping leading thereto and therefrom will automatically be maintained above the dew point of the conditioned air fed to the floors or rooms, whereby the need for drains and insulation is entirely eliminated.

This invention has for a further object an air conditioning and ventilating system in which air is supplied to a plurality of separate points of use in a building under a pressure sufficient to insure a desired amount of air passing from said points of use to the atmosphere and to prevent infiltration of air from the atmosphere; the volume of air supplied to said points of use being varied as the resistance to flow from said points of use varies because of external weather conditions, so that a minimum pressure is employed to obtain the desired passage of air to the atmosphere and to prevent the undesired infiltration from the atmosphere.

This invention also has for an object a ventilating and air conditioning unit in which the air to be conditioned is reduced to a temperature approaching the dehumidification temperature before it is passed through the dehumidifying element of the unit and is heated to a temperature approaching that desired at the point of use after being dehumidified, the cooling and heating being carried out in such a manner that a portion of the heat abstracted is given back to the air after it is dehumidified. The other portion of the heat abstracted from the air is removed by a medium which is subsequently used to cool the compressed refrigerant, and the other portion of the heat given to the air after dehumidification is supplied by the condensed partly cooled refrigerant so that in carrying out this heating the refrigerant is cooled to a temperature approaching the dehumidification temperature.

The particular nature of the invention, as well as other objects and advantages thereof, will ap-

pear most clearly from a description of preferred embodiments thereof, as shown in the drawings, wherein

Figure 1 is a section view, taken on line 1—1 of Figure 2, of a building in which an embodiment of the air conditioning and ventilating system of the invention, shown in a diagrammatic manner, is installed.

Figure 2 is a sectional plan view of a floor of the building taken on line 2—2 of Figure 3.

Figure 3 is a section elevation of a corridor of the building taken on line 3—3 of Figure 2.

Figure 4 is a view similar to Figure 3 showing certain arrangements used to control the air flow.

Figure 5 is a diagrammatic view of another preferred embodiment of the air conditioning unit of my invention.

Figure 6 is a front view of the automatic pressure operated air flow control device of my invention.

Figure 7 is an end sectional view taken on line 1—1 of Figure 6.

Figure 8 is a sectional view taken on line 8—8 of Figure 6 showing certain construction details.

Figure 9 is a front view of the combined heat exchange and ventilating unit with a portion of its casing broken away to show its internal construction.

Figure 10 is a view similar to Figure 9, showing a modified unit, and Fig. 11 is a detail view of the flow-control device of Fig. 4.

Referring to the drawings:

The building 10 is typical of the buildings to which the air conditioning and ventilating system of this invention is best adapted. Building 10 includes floors 11 whose floor space is unobstructed by partitions and the like, and floors 12, one only being shown, which are divided by partitions 13 into a plurality of rooms 14, and a main corridor 15. Doors 16 serve to communicate corridor 15 with rooms 14. Building 10 is also provided with windows 17 and outside doors, not shown. Windows 17 may be of any construction but must allow sufficient air leakage through them in the closed position for the purpose explained hereinafter.

The air is conditioned in an air conditioning unit 18, located in the basement of building 10, and is forced under pressure by blower 19 through an air duct 20 located in one of the walls 21 of building 10 to outlets 22, located adjacent the ceiling of each floor. The use of a separate duct 20 to lead the conditioned air to the floors 11 and 12 is optional, as the air can be led if desired to floors 11 and 12 through any convenient vertical shaft, such as an elevator shaft, a piping shaft, a stair case, etc.

In floors 11, the air passes through openings 22 directly to the space to be ventilated, but in floors 12, it flows through the corridor 15 and from thence through openings 23 in partitions 13 to the rooms 14. Openings 23 may occupy the positions of the usual transoms. If desired, openings 23 may be omitted and the conditioned air passed from corridors 15 to rooms 14 through the crannies and cracks in and around the doors 16 and their jams. In any event, the air conditioned in unit 18 flows under pressure from duct 20, through corridors 15 and from thence to rooms 14. The pressure under which the conditioned air is maintained by blower 19 should be just sufficient to prevent infiltration from the atmosphere and to allow a sufficient amount of air to escape from rooms 14 or floors 11 to maintain the air therein wholesome and suitable for

the occupants, or for the purpose to which the room is put. It has been found entirely feasible to operate the system with standard partition doors closed tight and with weather stripped windows, as the relative size of the crack around the partition door referred to the crack around a weather stripped window is of the order of magnitude of 5 to 1.

With the system so far described, if one of windows 17 is opened, the floor 11 or the room 14 which communicates to the atmosphere through the particular window 17 will have its pressure reduced to zero. Thus the pressure differential between the floor 11 or room 14 mentioned and the unit 18 will be greater than the differential between any other part of the building and unit 18 with the result that the greater volume of the air conditioned in unit 18 will tend to flow to the floor 11 or room 14 mentioned and the rest of the floor and rooms of the building will get less than their predetermined amount of conditioned air. To prevent such an undesirable occurrence, each of the openings 22 and 23 is provided with a pressure operated device 24, best shown in Figures 6, 7, and 8, which automatically prevents the undesired flow of air above mentioned when any part of the building is put in direct communication with the atmosphere.

Pressure operated device 24 includes a rectangular metallic frame 25 of a size to snugly fit into the intended one of openings 22 or 23. To the vertical sides of frame 25 are fastened bushings 26 in which are journaled the ends of rods 27. Each of rods 27 has fixed thereto a bent sheet metal member 28 of sufficient length to overlap the next lower member 28 when device 24 is in the closed position. The corners of the high pressure side of all but the bottom one of members 28 are cut away so as not to interfere with bushings 26 when device 24 is closed. The lower end of the low pressure side of each of members 28 is cut away at regular intervals to provide tabs upon which may be placed the proper amount of slotted weight bars 29, one only being shown, which are held in place by cotter pins 30, or similar means. The amount of bars 29 used must be sufficient to maintain the members 28 in the position shown in Figure 7, when the predetermined pressure differential exists between the high and low pressure sides of device 24, in other words, during normal air flow therethrough. Device 24 is so constructed that when in the closed position, it does not completely prevent the passage of air therethrough.

If for any reason the pressure at the low pressure side of device 24 should be reduced below the predetermined value, the torque exerted by the static pressure on the high pressure side of members 28 will no longer be balanced by torque exerted by the static pressure on the low pressure side and weight bars 29 with the result that members 28 will rotate in a counterclockwise direction to the closed position to thereby reduce the flow of air therethrough. This closing movement is accelerated by the pressure of flow developed by the initial high velocity flow of the air through device 24. When communication to the atmosphere is again cut off, the leakage of air through device 24 will rapidly bring the floor 11, corridor 15, or room 14 back to its predetermined pressure. Thus the pressure differential will diminish and the torque exerted by the static pressure on the low pressure side and by weight bars 29 increase to the point where it will be sufficient to rotate members 28 in a clockwise

direction to carry them back to their normal position. By the provision of devices 24 in openings 22 and 23, it is impossible for the system to be disorganized by reason of the opening of windows, doors, etc.

Rooms 14 and floors 11 are each provided with combined heat exchange and ventilating units 31. For purposes of illustration, one unit 31 is shown in each of rooms 14 and two units 31 in each of floors 11. Each of units 31 is supplied with heat exchange fluid by pipe 32, which is connected through pipe 33 to the heat exchange fluid supply line 34. The heat exchange fluid, after passing through unit 31 is returned to the heat exchange fluid return line 35 by pipes 36 and 37. Unit 31, see Figure 9, includes a casing 38 having a grilles aperture 39 near its bottom and a grilles aperture 40 near its top. Within casing 38 and near the bottom thereof is supported a fan unit which includes motor 41 and fans 42, one fan only being shown. Above the fan unit, is a heat exchanger 43 which comprises a coil of finned tubes through which the heat exchange medium is adapted to pass. The inlet end of heat exchanger 43 is connected to pipe 32 and the outlet end is connected to pipe 36. In the inlet of exchanger 43 is provided a valve 44 for regulating the amount of heat exchange medium passed through exchanger 43. This valve 44 is controlled by a diaphragm 45 which is connected through capillary tube 46 to a settable thermostat 47. A thermostat 47 is conveniently located in each of floors 11 and rooms 14.

The fans 42 take in air from the bottom of floors 11 or rooms 14 through aperture 39 and pass it through heat exchanger 43 to modify its temperature and then pass it back into the upper part of floor 11 or room 14, through aperture 40. By setting each of thermostats 47 to the temperature desired, the heat exchange fluid passed through each of exchangers 43 will be controlled to bring and maintain the whole body of air in each of the floors 11 and rooms 14 to the desired temperatures. Units 31 cause a continuous circulation and mixing of the air in each of floors 11 and rooms 14 so that the air in each of floors 11 and rooms 14 is substantially homogeneous both as to moisture content and temperature.

A settable thermostat 48 is soldered or otherwise substantially made a part of the surface of the coil of heat exchanger 43 and is connected to capillary tube 49 for purposes set forth herein-after.

The sensible cooling performed by units 31 can also be accomplished by direct cooling surface embedded in the external and partition walls of the conditioned area. It is to be noted that there is a double circulation of air in each of rooms 14 and floors 11; that is, a circulation from unit 18 through rooms 14 and floors 11 to the atmosphere, and a separate circulation in each of rooms 14 and floors 11 due to the units 31.

In order to provide means for controlling the amount of conditioned air supplied to each of the floors 11 and 12, the frame 25 of each of devices 24 located in conduit 20 is extended to house a damper 50 of the usual construction, as shown in Figs. 4 and 11. On the top of each of the extensions of frame 25 is mounted a motor 51 which, through mechanism of known character, not shown, is adapted to change the setting of damper 50. Motor 51, at first floor 11, is connected by a cable 52 to a control device 53; motor 51, at the second floor 11, is connected by a cable 75

54 to a control device 55; and motor 51 at the third floor 12 is connected by a cable 56 to a control device 57. Control devices 53, 55, and 57 are located in the basement of building 10, so as to be within easy reach of the operator of unit 18. Cables 52, 54, and 56 are not intended to represent a single wire but the usual number of wires used to control motors at a remote point. By operating control devices 53, 55, and 57, the settings of each of the dampers 51 may be altered at will to allow a greater or lesser volume of air to pass to each of floors 11 and 12.

By reason of dampers 51, it is possible to change the resistance offered to the flow of conditioned air into the floors 11 and 12 so that a predetermined amount of air may be passed through the floors into the atmosphere and infiltration prevented in spite of change of resistance to the flow of air to the atmosphere. Thus, if the resistance to the flow of the air from the rooms 14 or floors 11 to the atmosphere is increased or diminished, as for instance, due to wind conditions outside of the building, all, or the necessary ones, of dampers 51 may be moved to decrease or increase the resistance to the flow of conditioned air into any one or all of the floors 11 and 12.

In order to determine when a change of resistance to the flow of air from floors 11 and 30 rooms 14 to the atmosphere has taken place and the amount of the change, a U-manometer tube 58, having one end opening into the atmosphere, is provided in the basement of the building. The other end of U-tube 58 is connected to a header 35 59 to which are connected tubes 60, 61, and 62. A valve is provided in each of tubes 60, 61, and 62. Tube 60 opens on the first floor 11; tube 61, on the second floor 11; and tube 62 opens on the third floor 12. Thus, by opening the appropriate 40 valve, the pressure difference between the atmosphere and any of the floors 11 and 12 may be observed by the operator of unit 18 and he may then adjust dampers 51 as required to maintain the required flow through the floors 11 45 and 12.

If, after the system is installed and adjusted, it is desired to put a floor 11 or 12 to a new use which requires a greater or lesser amount of conditioned air than the previous use, the damper 51 controlling that floor 11 or 12 is set to offer the proper resistance to the flow of conditioned air and the weights 29 of the device 24 which controls the conditioned air supplied the particular floor 11 or 12, changed as made necessary by 55 the new pressure differential. Thus the system is flexible and the amount of air supplied to any floor 11 or 12 may be altered at will.

Dampers 51 may, if desired, be provided on the low pressure side of the devices 24 which 60 control the passage of the conditioned air into the rooms 14 to secure a further regulation and control of the amount of conditioned air supplied to each of rooms 14.

Unit 18 comprises a shell 63 in which is housed 65 heat exchangers 64, 65, 66, and 67, dehumidifier 68, separator 69, and humidifier 70. Each of the heat exchangers 64, 65, 66, and 67 and dehumidifier 68 is made up of a plurality of banks of tubes, three being shown. One end of the tubes of 70 each bank is fastened in an inlet header and the other end of the tubes of each bank is fastened in an outlet header. The outlet header of the first bank is connected to the inlet header of the second bank and the outlet header of the second 75 bank is connected to the inlet header of third

bank. By this arrangement, the fluid passed to the inlet header of the first bank flows through the tubes of the first bank to the outlet header of the first bank, then to the inlet header of the second bank, through the tubes of the second bank to the outlet header of the second bank, and then to the inlet header of the third bank, through the tubes of the third bank to the outlet header of the third bank. The separator 69 may be made up of a plurality of bent or corrugated spaced plates, as is well known in the art. The humidifier 70 comprises a water spraying means such as a spray nozzle or a bank of spray nozzles.

The heat exchangers 64, 65, 66, and 67, the dehumidifier 68 and the separator 69, are so located within shell 63 that the air in flowing from the air inlet 71 to the air outlet 72 comes into intimate contact with the heat exchange or separating surface of each of them.

Associated with unit 18 is a refrigerating plant 20 13 which comprises a motor driven compressor 14 and a condenser 15. The refrigerant, after being compressed in compressor 14, flows through pipe 16 to the bottom of condenser 15; from the top of condenser 15, it flows through pipe 17 to 25 the inlet of heat exchanger 67. From the outlet of heat exchanger 67, it flows through pipe 18 and expansion valve 19 to a heat exchanger 80, in which it abstracts heat from the heat exchange fluid returning from units 31 through line 30 35. From heat exchanger 80, the expanded refrigerant passes through pipe 81 to the compressor 14. The heat exchange fluid, after being cooled in heat exchanger 80, passes through piping 82 and pump 83 to dehumidifier 68. From 35 dehumidifier 68, the heat exchange fluid passes to line 34.

Heat exchanger 64 has its inlet header connected by pipe 84 to the city water mains or other source of cooling water supply, and its outlet header, which is adjacent air inlet 71, connected through pipe 85, to the sprayer 86, which passes cooling water over the coils of condenser 15. A pan 87 collects the water falling from condenser 15 and pipe 88 leads it to the sewer or 45 other point of disposal.

Heat exchanger 65 has its outlet header disposed adjacent the inlet header of heat exchanger 64. A pipe 89 connects the outlet header of heat exchanger 65 to the inlet of a pump 90. The outlet of pump 90 is connected through pipe 91 to the inlet header of heat exchanger 66, the outlet header of which is adjacent the separator 69, and is connected through pipe 92 to the inlet header of heat exchanger 65. By this arrangement, a closed path for the circulation of a heat exchange fluid such as water or the like is provided for purposes to be explained hereinafter.

The humidifier 70 is connected by a valved line 93 to a water supply. This water may come directly from the city mains or, for winter use, may be heated. Steam condensate from the heating system is preferably used for supplying the energy of humidification. A pipe 94 leads the water separated at separator 69 to the sewer or other point of disposal.

The air entering inlet 71 first comes into contact with the tubes of heat exchanger 64 and gives up heat thereto; by reason of this counter-current exchange of heat, the air is cooled to substantially the temperature of the water supplied to heat exchanger 64, and the water heated to substantially the temperature of the incoming air. The air then comes into contact with the tubes of heat exchanger 65, and gives up heat thereto; 70 75

by reason of this counter-current exchange of heat, the air is further cooled to a temperature mentioned hereinafter and the water flowing through heat exchanger 65 heated to a temperature in the neighborhood of the temperature of the water supplied to heat exchanger 64. The air then passes through dehumidifier 68 and separator 69, wherein it is brought to the desired dew point and the excess moisture removed. The 5 finally cooled and dehumidified air then passes through heat exchanger 66 wherein it is heated to a temperature in the neighborhood of the temperature of the water supplied to heat exchanger 64 and the water cooled to a temperature in the 10 neighborhood of the dew point of the dehumidified air. Since this heat exchange medium passes through pipe 92 to heat exchanger 65, the temperature of the air leaving heat exchanger 65 is also in the neighborhood of the dew point of the 15 conditioned air.

Since the compressed refrigerant is cooled in condenser 75 by the water leaving heat exchanger 64, it reaches heat exchanger 67 at about the temperature of the atmospheric air in extreme weather and considerably above it in mild weather. The partly heated dehumidified air, in passing through heat exchanger 67, is heated to a temperature in the neighborhood of atmospheric air and the condensed refrigerant is cooled to a 20 temperature in the neighborhood of the temperature of the water supplied to heat exchanger 64. From this, it should be obvious that the heat removed from the air in heat exchanger 64 is a clear gain to the system.

In referring to the temperatures to which the air and the various heat exchange mediums are heated or cooled in unit 18, it is to be appreciated that the temperatures mentioned are the temperatures theoretically possible and that in 35 the actual systems such temperatures are not obtainable but can only be approached. It is also to be understood that by the regulation of the amounts of the heat exchange mediums passed through the various heat exchangers, the heating and cooling of the air, and the heat exchange mediums may be varied within considerable limits. Thus, for example, by reducing the amount of water circulated through heat exchangers 65 and 40 66, the air, when it reaches heat exchanger 67, may be of a sufficiently low temperature to cool the compressed refrigerant flowing therethrough to within a few degrees of the dew point of the 45 conditioned air.

The capillary tube 49 previously mentioned is 50 connected to a diaphragm 94' that controls a settable thermostat 95. A branched capillary tube 55 96 connects thermostat 95 to a diaphragm 97 that controls expansion valve 79 and to a diaphragm, not shown, in motor control device 98 that controls the motor of compressor 74. In this arrangement, thermostat 48 is called the master thermostat and thermostat 95 is called the sub-master thermostat. The function of thermostat 48 is to control the setting of thermostat 95 and 60 the function of thermostat 95 is to control, through diaphragm 97 and motor control device 98, the expansion and the compression of the refrigerant. The thermostat 48, chosen as the master thermostat, is the one located in the floor 65 11 or room 14 which is to be kept at the lowest temperature. This thermostat 48 is set at the desired temperature, for instance, 60° F. and will operate through capillary tube 49 and diaphragm 94 to set thermostat 95 to a temperature somewhat below this, for instance, 55° F. If the air 70 75

leaving the dehumidifier 68 is above the latter temperature, diaphragm 97, through capillary tube 96, will increase the opening of expansion valve 79 to lower the temperature of the refrigerant and consequently the temperature of the water leaving 5 heat exchanger 80 and motor control device will increase the speed of the motor of compressor 74. If the air leaving dehumidifier 68 is below 55° F., then thermostat 95 is effective to cause a decrease in the opening of expansion valve 79, and a reduction in the speed of the motor of compressor 74. By this arrangement, it is possible to control the dew point of the conditioned air in accordance with the requirements at the floor 11 or room 14 chosen and from a point remote from conditioning 15 unit 18.

The arrangement of master and sub-master control thermostats 48 and 95 is desirable as it increases the ease of control and efficiency of the air conditioning and ventilating system of my 20 invention, but it may be dispensed with. Whether the arrangement just mentioned is used or not, the temperature of the water circulated through line 34 and units 31 is always at a temperature somewhat above the dew point of the air and for 25 that reason there is no necessity of insulating line 34.

In the system just described, the air is cooled to a temperature in the vicinity of the dehumidification temperature before it is passed through 30 the dehumidifier so that the amount of work done in the dehumidifier is reduced to a minimum and the size of the refrigeration plant necessary to do the work is also kept to a minimum. This system makes it possible to bring the refrigerant to a temperature in the vicinity of the desired dew point before expanding it; thereby further reducing the amount of refrigerant necessary to do the required cooling. The system further makes it possible, in the summer time, to heat 35 the air to a usable temperature without addition of outside heat to the system, considering the refrigeration plant as part of the system. Also, with this system, heat exchange fluid is supplied to units 31 at a temperature which renders it 40 impossible for the units to be brought below the dew point of the conditioned air, thus eliminating the necessity of drains for units and insulation 45 for lines 34 and 35.

The system, as described, is intended primarily 50 for summer operation; i. e., operating under conditions which render it desirable to both dehumidify and cool the air. However, the system is also adapted for winter operation; i. e., operation under conditions which render it desirable to 55 humidify and heat the air.

For operating under winter conditions, refrigeration plant 73 is not operated, water is not supplied to heat exchanger 64, and pump 90 does not circulate water through heat exchangers 65 and 60 66. On the other hand, the valve in pipe 93 is opened to supply water to the spray nozzles of humidifier 70; the valve in steam line 99 which connects to injector 100 is opened and the valve in line 101 is connected, in a manner not shown, to a float operated valve control mechanism, located in heat exchanger 80, not shown, to maintain the amount of heated water circulated through the system constant.

With the system so arranged, the air entering 70 inlet 71 is heated by passing through dehumidifier 68, now used as a heater, and picks up the desired moisture by passing through the humidifier 70. Thus heated and humidified, the air is forced by blower 19 through duct 20, in the manner pre- 75

viously set forth, to rooms 14 and floors 11. The heated water, after passing through dehumidifier 68, enters the supply line 34 and passes to units 31 where it is used to heat the air in rooms 14 and floors 11 to a temperature desired by the occupants. The water is then returned to return line 35 and again heated at heat exchanger 80 that it may repeat the cycle just set forth.

If desired, the system may be modified to circulate the refrigerant instead of water through dehumidifier 68, line 34, unit 31, and line 35 to thus further increase the efficiency of the system and reduce its initial cost. With the system thus modified, referring to Figure 5, pipe 78 is made to connect the outlet header of heat exchanger 67 with the inlet header of dehumidifier 68; expansion valve 79 is located in pipe 78 adjacent the inlet header of dehumidifier 68, and line 35 is connected to the intake of compressor 74. The condensed refrigerant will then pass from heat exchanger 67 through pipe 78 and be expanded in passing through valve 79. From valve 79, the expanded refrigerant will pass through dehumidifier 68, line 34, unit 31, and back to compressor 74, through line 36. Except for the particulars just noted, the modified system will operate in the same manner as the system previously described.

For winter operation, still referring to Figure 5, water is not passed through pipe 84, the refrigerant plant 73 and pump 90 are not operated and valves 102 and 103, in pipe 78 and line 35 respectively are closed. However, the valve in line 93 is opened to supply water to dehumidifier 90 and valves 104 and 105 are opened to place the water heating unit 106 in communication with pipe 78 and line 35. Water heating unit 106 includes a hot water tank 107, a steam injector 108 to which steam is supplied by valved pipe 109, a valved overflow pipe 110, a pipe 111 for connecting line 35 with tank 107, a pump 112 which passes the heated water from tank 107 through pipe 113 to pipe 78, and float actuated device, not shown, for controlling in line 110.

With the system so arranged, pump 112 passes heated water from tank 107 through pipes 113 and 78 to dehumidifier 68, which is now used as an air heater. From dehumidifier 68, the heated water passes through line 34 to units 31 and from units 31 back to hot water tank 107, through line 35 and pipe 111. The air entering inlet 71 is heated the desired amount in passing through dehumidifier 68 and picks up the required moisture in passing through humidifier 70, the excess water being removed as the air passes through separator. The thus heated and humidified air is then passed by blower 19 through conduit 20 to floors 11 and 12, corridors 15 and rooms 14, where it is further heated as desired by units 31.

When an ample supply of sufficiently cold water is available the system of the invention may be modified to use such water as the heat exchange medium passed through units 31. When the system is so modified, the outlet header of dehumidifier 68 of Figure 1 is connected to the water inlet of heat exchanger 80 and the outlet header of dehumidifier 68 of Figure 5 is connected to the intake of compressor 74. Line 34 of both Figures 1 and 2 is connected to the water supply line 99 and the return line 35 also of both Figures 1 and 2 is connected to pipe 84 or led to the sewer or other place of disposal. The construction and operation of the system is otherwise unchanged, with the exception that units 31 are modified as shown in Figure 10.

The modified units 31 are provided with a second valve 114 in the inlet of exchanger 43. This valve is operated by a diaphragm 115 which is connected to settable thermostat 48 by a branch of capillary tube 49.

With the system thus modified, the air is conditioned in unit 18 and is supplied to floors 11 and 12 and rooms 14 as before described. Thermostats 47 in each of floors 11 and rooms 14 are also, as previously, set to maintain the temperature desired in each of said floors 11 and rooms 14 and diaphragms 46 and valves 44 also function as previously described to maintain such desired temperatures. However, with the modified system, each of thermostats 48 must be set at a temperature corresponding to or above the dew point of the air. Thus set, thermostats 48, through capillary tubes 49, and diaphragms 115, will so control the amount of water passing valves 114 that the temperature of the tubes and fins of heat exchanger 43 will always be maintained at a temperature above the dew point of the air conditions in unit 18. The master and sub-master thermostatic control of the dew point of the air conditioned from a selected one of the floors 11 or rooms 14 is also applicable to the modified system.

While preferred embodiments of the invention have been shown and described, it will be understood that the invention may be embodied in other forms and various changes made without departure from its principle as defined in the appended claims.

I claim:

1. In a building having a plurality of rooms, a ventilating system comprising a main air conditioning unit, means for conducting conditioned air from said unit to each of said rooms, said air conducting means including a fan for maintaining a predetermined air pressure in the said rooms sufficient to prevent infiltration of atmospheric air and to permit a desired amount of air to filter out of each room to the atmosphere, and pressure operated means operable upon a substantial reduction of pressure in any one of said rooms to cut off the normal supply of air to the one or ones of said rooms in which the substantial reduction of pressure has taken place.

2. In a ventilating system, an air conditioning unit, a place of use for the conditioned air, means for passing conditioned air from said unit to said place of use and from said place of use to the atmosphere, and means for maintaining a substantially constant pressure differential between said place and the atmosphere while maintaining the pressure at said unit substantially constant, said last-mentioned means comprising a pivoted member having spaced depending surfaces of such extent as to close the passage for conditioned air to the place of use upon rotation in either direction from the normal open position of said pivoted member.

3. In a ventilating system, the combination of an air conditioning unit, a plurality of places of use for the conditioned air, each of said places of use having conditioned air inlets and means of fixed resistance allowing passage of air to the atmosphere, means for passing conditioned air from said unit to each of said conditioned air inlets, adjustable dampers in each of said air inlets for regulating the resistance offered by each of said air inlets to the flow of air therethrough, said dampers embodying movable pressure-responsive flow-controlling members whereby predetermined pressure differentials are maintained

between said places of use and the atmosphere in spite of changing atmospheric conditions.

4. In a ventilating system, an air conditioning unit, means for conducting conditioned air from said unit to a place of use, means allowing a predetermined volume of air to pass from said place of use to the atmosphere at a predetermined pressure differential between said place of use and the atmosphere, and pressure-operated means operative to prevent abnormal flow of air from said place of use to the atmosphere upon the opening of a window or other relatively large vent between said place of use and the atmosphere and for varying the resistance to air flow of said air conducting means whereby the predetermined pressure differential between said place of use and the atmosphere may be maintained in spite of varying atmospheric conditions.

5. In a ventilating system the combination of an air conditioning unit, a plurality of places of use for the conditioned air, each of said places of use having a conditioned air inlet and means allowing passage of air to the atmosphere, means for conducting conditioned air under pressure from said unit to each of said inlets to establish a normal flow of air to each of said places of use and from said places of use to the atmosphere, and adjustable pressure-operated damper means in each of said inlets operable to maintain normal flow through said inlets under varying atmospheric conditions and to prevent abnormally large flow of conditioned air to one of said places of use.

6. In a building having a plurality of rooms, a ventilating system comprising a main air conditioning unit, means for conducting conditioned air from said unit to each of said rooms, means for supplying positive volumes of air to each room under varying external atmospheric pressures adjacent the respective rooms, temperature modifying means in each of said rooms, means for supplying heat exchange medium to said temperature modifying means, means in each of said rooms affected by the temperature of the air therein effective to control the supply of heat exchange medium to the temperature modifying means, and means affected by the temperature of the temperature modifying means effective to further control the supply of heat exchange medium to the temperature modifying means to prevent the temperature of the temperature modifying means being brought below the dew point of the air in the room.

7. In a building having a plurality of rooms, a ventilating system comprising a main air conditioning unit, means for conducting conditioned air from said unit to each of said rooms, a heat exchanger in each of said rooms comprising a plurality of connected tubes, means for supplying heat exchange medium to each of said heat exchangers and means for controlling the heat exchange fluid supplied to each of said heat exchangers whereby the temperature of the air in each room may be maintained as desired by the occupant of the room and the temperature of the heat exchanger in each room maintained above the dew point of the air, said supply control means including a thermostat affected by the temperature of the air and a thermostat affected by the temperature of the heat exchanger.

8. A ventilating system comprising a main air conditioning unit including dehumidification means, means for conducting air from said unit to a point of use, temperature modifying means

at said point of use, means for passing heat exchange medium through said dehumidification means, means for passing heat exchange medium through said temperature modifying means, means for supplying the heat exchange fluid issuing from said dehumidification means to said temperature modifying means and heat exchange means for preheating the air before it is conducted to the point of use by contact with the heat exchange fluid being supplied to the dehumidification means.

9. A ventilating system comprising a main air conditioning unit, means for conducting air from said unit to a point of use, means at said point of use for modifying the temperature of the air thereat, said unit including a heat exchanger for the dehumidification of the air having a heat exchange medium inlet and heat exchange medium outlet, said temperature modifying means including a heat exchanger having a heat exchange medium inlet and a heat exchange medium outlet, means for connecting the outlet of the heat exchanger at the unit with the inlet of heat exchanger to the temperature modifying device and heat exchange means for preheating the dehumidified air from said first mentioned heat exchanger by contact with the heat exchange medium supplied to said first mentioned heat exchanger.

10. In a building having a plurality of rooms, a ventilating system comprising an air conditioning unit, means for conducting conditioned air from said unit to each of said rooms, means for supplying positive volumes of air to each room under varying external atmospheric pressures adjacent the respective rooms, temperature modifying means in each of said rooms, means for maintaining the temperature of said temperature modifying means above the dew point of the air in the room and means affected by the temperature of said temperature modifying means for controlling the conditioning of the air at said unit.

11. In an air conditioning and ventilating system, an air conditioning unit including a dehumidifying section and having associated therewith the expansion valve and compressor of a refrigeration plant, means for conducting conditioned air from said unit to a place of use, temperature modifying means at said place of use, means including settable means in said section affected by the temperature of the air leaving said section effective to control said valve and said compressor, and settable means affected by the temperature of said temperature modifying means effective to set said settable means in said section.

12. In an air conditioning and ventilating system, an air conditioning unit including a dehumidifying section and having associated therewith a refrigeration plant for supplying cooling medium to said section, means for conducting conditioned air from said unit to a place of use, temperature modifying means at said place of use, means including settable means in said section affected by the temperature of the air leaving said section effective to control the operation of said plant to vary the characteristics of the cooling medium supplied to said section, and settable means affected by the temperature of said temperature modifying means effective to set said settable means in said section.

13. In an air conditioning and ventilating system, an air conditioning unit including a dehumidifying section having associated therewith

- the expansion valve and compressor of a refrigeration plant, a settable thermostat in said section affected by the temperature of the air leaving said section, means operated from said thermostat for controlling said expansion valve, means 5 operated from said thermostat for controlling the operation of said compressor, means for conducting air from said unit to a place of use, a temperature modifying means at said place of use, 10 a settable thermostat at said temperature modifying means adapted to be affected by the temperature of said temperature modifying means, and means at said section operated from said second thermostat for setting said first thermostat.
14. In an air conditioning and ventilating system, an air conditioning unit including a de-humidifying section and having associated therewith a refrigerating plant for supplying cooling 20 medium to said section, a settable thermostat in said section affected by the temperature of the air leaving said section, means operated from said thermostat for controlling the operation of said refrigerating plant to vary the characteristics of 25 the fluid supplied to said section, means for conducting air from said unit to a place of use, a temperature modifying means at said place of use including a coil having a valved inlet and an outlet for heat exchange medium, a settable thermostat 30 fixed to said cooling coil to be affected by the temperature of said coil, means operated from said second thermostat for controlling said valved inlet and means also operated from said second thermostat for setting said first thermostat.
15. In a building having a plurality of rooms, a ventilating system comprising a main air-conditioning unit, means for conducting conditioned air from said unit to each of a plurality of said rooms, means for causing circulation of 40 conditioned air through said air conducting means to the rooms at a pressure sufficient to prevent infiltration of outside air to any of the rooms under ordinary conditions, and means for independently controlling the supply of conditioned air to each of said plurality of rooms and responsive to the reduction of pressure caused by opening a window in one of the rooms to cut off the 45 supply of conditioned air thereto.
16. In a building having separate rooms, a ventilating system comprising a main air-conditioning unit, means for forcing conditioned air from 50 said unit to each of a plurality of said rooms under pressure sufficient to prevent infiltration of outside air to any of the rooms under ordinary conditions and pressure-responsive flow-controlling means for regulating the flow of conditioned air to each of said plurality of rooms, said flow-controlling means being responsive to the pressures in each of said plurality of rooms and the 55 pressure of the conditioned air to insure the desired supply of air to each of said plurality of rooms irrespective of variations in the external atmospheric air pressures on said rooms.
17. In a building having separate rooms provided with vent openings to the atmosphere of a size to permit limited exfiltration of air from each room to the atmosphere under normal pressure conditions in the rooms, a ventilating system comprising a main air-conditioning unit, means for 60 forcing conditioned air from said unit to each of a plurality of said rooms at a pressure sufficient to produce exfiltration of room air to the atmosphere under ordinary conditions, and pressure-responsive means for controlling the flow of air 65 from said air conditioning unit to each of said 70 rooms.

plurality of rooms, said pressure-responsive means being affected by the pressures of the air in said plurality of rooms and the pressure of the conditioned air supplied by said unit.

18. In an air conditioning system provided with an air supply duct connected to a space to be ventilated, air conditioning means to condition the air supplied through said duct to said space, regulating means for said air conditioning means responsive to the condition of the air in the system and means controlled by the pressure of the air in said supply duct and in the space to be ventilated for varying the amount of air supplied through said duct to the ventilated space.

19. In a building having a plurality of rooms, 15 a ventilating system comprising an air conditioning unit, means for conducting conditioned air from said unit to each of said rooms, air cooling means in each of said rooms for bringing and maintaining the air to the temperature desired 20 by the occupant, and means affected by the temperature of the air cooling means in the room to be maintained at the lowest temperature for controlling said air conditioning unit to maintain the dew point of the air conditioned in said 25 unit below the temperature of the air cooling means of said room, and means for controlling said air cooling means in each room in accordance with the temperature required therein.

20. An air conditioning system for an enclosure 30 with two streams of air intermingling within the enclosure including, means for introducing one of said streams of air into the enclosure, means for effecting the second stream of air within the enclosure, one of said streams having temperature 35 regulating means and the other having humidity varying means, a thermo-responsive device controlling both the tempering and humidity varying means, and a thermostat for controlling the temperature regulating means for 40 maintaining the required temperature in the enclosure.

21. An air conditioning system for an enclosure including means for introducing a stream of fresh air into the enclosure to maintain a substantially 45 constant differential pressure within the enclosure above the pressure outside thereof to produce an exfiltration of air therefrom, means within the enclosure to produce a second stream of air to circulate therein and commingle with 50 said first stream of fresh air, means for conditioning one of said streams of air to impart the desired humidity thereto, means for supplying tempering means to both streams of air, temperature responsive devices in the enclosure for controlling said humidity conditioning means and 55 tempering means, and a thermostat operable to regulate the temperature in the enclosure, whereby the required ventilation, humidity and temperature are maintained in the enclosure.

22. In an air conditioning system for an enclosure, an air conditioning unit with means for passing air therethrough to the enclosure, a heat exchange member in the conditioning unit, a heat exchange member in the enclosure, and 65 means for circulating a heat exchange medium first through the heat exchange member in the conditioning unit thereby modulating the temperature thereof and then through the heat exchange member in the enclosure.

23. In an air conditioning system for an enclosure, an air conditioning unit with means for passing air therethrough to the enclosure, a heat exchange member in the conditioning unit, a heat exchange member in the enclosure, means for 70 75

5 circulating a heat exchange medium first through the heat exchange member in the conditioning unit thereby modulating the temperature thereof and then through the heat exchange member in the enclosure, and a thermostat associated with the heat exchange member in the enclosure controlling the temperature of the heat exchange medium circulated through said heat exchange members.

10 24. In a building having a plurality of rooms, an air conditioning system including a main air conditioning unit with means for conditioning the air to a required humidity value and passing air therethrough to each room, air cooling means in each of said rooms, and means interconnected with the air conditioning unit and a room air cooling means for maintaining the temperature of said air cooling means in each room above the dew point of the air introduced into the rooms.

15 25. An air conditioning system including a conditioning unit in which air is conditioned with respect to its humidity, a second unit in which air is conditioned with respect to its temperature, and interconnected regulating means operable on the humidity conditioning means to condition the air to a predetermined absolute humidity value and to maintain the temperature of the temperature conditioning unit above the dew point temperature of the air passing through the humidity conditioning unit.

20 26. An air conditioning system for an enclosure comprising a conditioning unit through which air is passed for modifying one of its conditions on its way to the enclosure, a second conditioning unit associated with the enclosure modifying its other condition, means in one of the conditioning units for conditioning the air to an absolute humidity value, means in the other conditioning unit for conditioning the air to the required temperature, and interconnected regulating means between the two units to regulate the tempering

means in accordance with the dew point temperature of the air conditioned to said absolute humidity value to maintain the temperature of the temperature conditioning unit above said dew point temperature.

25 27. An air conditioning system for an enclosure comprising a conditioning unit through which air is passed for modifying one of its conditions on its way to the enclosure, a second conditioning unit associated with the enclosure modifying its other condition, means in one of the conditioning units for conditioning the air to an absolute humidity value, means in the other conditioning unit for conditioning the air to the required temperature, and interconnected regulating means between the two units to regulate the humidity varying means to reduce the dew point temperature of the air to a temperature below the temperature of the temperature conditioning unit.

30 28. In a building having a plurality of rooms each provided with an air inlet, a ventilating system including means for circulating air under pressure to said inlets, and an automatic flow-controlling device in the inlet to each room for admitting predetermined quantities of air from said unit to each of said rooms to maintain air pressure therein above the atmospheric pressure outside of the building but operable to restrict the flow of air upon a reduction of pressure on either side of the inlet.

35 29. In a building having a plurality of rooms each provided with an air inlet, a ventilating system including means for circulating air under pressure to said inlets, and an automatic flow-controlling device in the inlet to each room for admitting predetermined quantities of air from said unit to each of said rooms to maintain air pressure therein above the atmospheric pressure outside of the building but operable to restrict the flow of air through the inlet to a room upon a reduction of pressure in the room.

40 ROBERT B. P. CRAWFORD.
